UNITED STATES PATENT OFFICE.

WILLIAM R. HOYT, OF STAMFORD, CONNECTICUT, ASSIGNOR TO THE YALE & TOWNE MANUFACTURING COMPANY, OF STAMFORD, CONNECTICUT.

LOCK STRUCTURE.

Application filed April 25, 1924. Serial No. 708,988.

To all whom it may concern:

Be it known that I, WILLIAM R. HOYT, a citizen of the United States, and resident of Stamford, in the county of Fairfield and State of Connecticut, have invented certain new and useful Improvements in Lock Structures; and I do hereby declare the following to be a full, clear, and exact description of the invention, such as will enable others skilled in the art to which it appertains to make and use the same.

This invention relates to improvements in lock structures and has particular reference to means for adapting an ordinary lock and a strike to doors or other relatively movable members having rabbeted meeting edges,—one object of the invention being to provide simple means in the nature of a sheet metal auxiliary member whereby a lock casing having a flat front, such as a mortise lock casing of ordinary construction, may be utilized in one door for a "rabbeted lock" without removing or changing the front of the ordinary lock casing, and to provide also a sheet metal strike adaptable to the rabbeted portion of another door or member with which the door carrying the lock cooperates.

With this and other objects in view, the invention consists in certain novel features of construction as hereinafter set forth and pointed out in the claims.

In the accompanying drawings,—

Figure 1 is a perspective view showing a portion of a lock and my improved auxiliary member,—these parts being shown separated.

Figure 2 is a perspective view showing the parts assembled, and

Figure 3 is a perspective view of the strike.

In Figure 2 of the drawings, a fragmentary portion of a door 1 is shown as having a rabbet 2. A lock casing of the mortise type is represented at 3 and is so mounted in the door as to project partially into the rabbet 2. The front plate 4 of the lock is flat and projects above and below the upper and lower edges of the lock casing so as to form ears 5.

In adapting an ordinary flat front lock to a rabbeted door, I employ an auxiliary member or lock front 6 which is preferably made of sheet metal having ears 7 at its respective ends bent laterally from its body

portion and of such dimensions as to cover those portions of the lock casing 3 at the top and bottom of the latter, which project into the rabbet 2 of the door and to extend to and be flush with the walls of said rabbet,—the body portion of said auxiliary member covering the side portion of the lock casing within the rabbet 2. The auxiliary member 6 thus covers that portion of the lock casing 3 behind the front plate 4 which projects into the rabbet 2. The auxiliary member 6 is provided at or near its respective ends, with vertically disposed ears 8 which project from one side edge of the body portion of said member and are disposed behind the ears 5 formed by the upper and lower end portions of the front plate 4. The ears 5 of the front plate 4 are provided with suitable holes for the passage of fastening devices and the ears 8 are similarly provided with holes 9 for the passage of said fastening devices,—the auxiliary member 6 being thus secured in place by the same fastening devices which are utilized to secure the front plate of the lock 80 casing to the door.

With the use of my improvement as above described, a regular straight front lock can be transformed into a rabbeted front lock without removing or changing the regular front, by the simple addition of the auxiliary member or facing plate 6.

The other door or member with which the door 1 is to cooperate will be provided with a rabbet similar to the rabbet 2 shown in Figure 2 and receives a strike 10. This strike is preferably made of sheet metal and provided with openings 11 and 12 to receive, respectively, the latch 13 and dead bolt 14 of the lock. The strike is provided along one edge with a flange 15 bent at right angles to the body portion and at the upper and lower ends of said flange, ears 16 are provided and project from said flange at right angles thereto. When the doors are closed and the rabbeted portions thereof intermeshed, the flange 15 of the strike will lie parallel with the body portion of the auxiliary member 6 and the ears 16 will project over and under respectively, the upper 100 and lower ears 7 of the member 6.

Having fully described my invention what I claim as new and desire to secure by Letters-Patent, is:

1. A facing plate for a rabbeted lock pro-

vided at its upper and lower ends with ears to lie parallel with the upper and lower edges of the lock, said facing plate also having ears adapted to be secured to the front face of a lock.

2. An auxiliary facing plate for a rabbeted lock consisting of sheet metal and provided at its upper and lower ends with laterally projecting ears and also provided with ears which project laterally from a side edge of said facing plate.

3. The combination with a door or support having a rabbeted edge and a lock provided with a front plate, said lock mounted in the door or support and having a portion entering the rabbet in the same, of an auxiliary facing plate to lie against the exposed side face of the lock and provided with ears lying parallel with the top and bottom edge portions of the lock and covering the exposed parts of the same, said auxiliary fac-

ing plate also provided with ears secured to the front plate of the lock.

4. In a rabbeted lock structure, the combination with a door having a rabbeted portion, and a lock mounted in said door and projecting into the rabbeted portion thereof, of a facing plate or member covering the exposed top, bottom and side portions of the lock, means for securing said facing plate in place, and a strike adaptable to the rabbeted portion of another support and comprising a body portion having openings, and a flange at right angles to one edge of said body portion.

In testimony whereof, I have signed this specification in the presence of two subscribing witnesses.

WILLIAM R. HOYT.
